UNITED STATES PATENT OFFICE

MAURICE DUSHEK, OF CHICAGO, ILLINOIS

DESIGN FOR A CONFECTION

Application filed August 29, 1929. Serial No. 32,618. Term of patent 7 years.

To all whom it may concern:

Be it known that I, MAURICE DUSHEK, a citizen of the United States, residing at Chicago, in the county of Cook and State of Illinois, have invented a new, original, and ornamental Design for a Confection, of which the following is a specification, reference being had to the accompanying drawing, forming part thereof.

In the drawing, Fig. 1 is a face view of the candy or confection, showing my new design; and

Fig. 2 a section taken substantially on line 2—2 of Fig. 1.

I claim:

The ornamental design for a confection as shown.

MAURICE DUSHEK.
